UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

RAILWAY-CAR CONSTRUCTION

Application filed February 18, 1929. Serial No. 340,731.

The invention relates to railway cars, and more particularly, to means for attaching an end wall structure to a railway car. A very common end wall structure in use comprises a plurality of corrugated or embossed metallic plates secured together along horizontal lines and flanged adjacent their vertical edges, which flanges are secured together and to the upper and lower longitudinal frame members of the car. In such a structure the impact of the shifting cargo against the end wall is carried by the embossments acting as beams to the vertical flanges, which united flanges then become a horizontally loaded vertical beam between the upper and lower longitudinal frame members of the car.

The place of attachment of the flanges of the adjacent sheets forms a weak spot in the above mentioned vertical beam and it is an object of this invention to reinforce this weak spot with a member which is a splice, a stiffener and also forms means for attachment of diagonally upwardly and diagonally downwardly extending braces which are secured to the side plate and side sill, respectively, of the car. This splice plate and the diagonal braces may be made of one piece if desired.

As this member is tied to the upper and lower horizontal frame members of the car, the above mentioned vertically disposed beam is supported at points intermediate its ends which enable such a beam to carry a considerably greater load than if the beam was supported merely at its ends.

The vertically disposed beam thus reinforced will also perform the usual functions of the corner post or end frame member of the car, as the splice plate and diagonal braces also strengthen it as a column. The end post forms a part of the side truss of the car which carries the load of the lading, therefore, my construction is desirable in a car end having the sheets secured together along vertical lines.

In the drawings:

Fig. 1 shows an elevation of a railway car with my invention applied thereon.

Fig. 2 is a partial side elevation of the same car.

Figs. 3 to 8 show enlarged variations of my construction.

End walls for railway cars now in general use comprise an upper (preferably corrugated) plate 2 overlapping and secured to a lower (preferably corrugated) plate 3 on a substantially horizontal line 4. These plates are provided with flanges 5—6 adjacent their vertical margins with the flanges (5) of the upper sheet overlapping and secured to the flanges (6) of the lower sheet. These flanges are secured (directly or indirectly) to the side plate 7 and side sill 8, respectively, so that the end wall and the flanges perform the functions of the usual corner post of the car. The member 10 is attached to the upper and lower flanges and extended to provide means for attachment of the upwardly (11) and downwardly (12) extending braces which are secured at their opposite ends to the side plate 7 and side sill, respectively.

In the form shown in Figs. 1, 2 and 3 the member 10 comprises a flat plate preferably positioned outside of the flanges to which the upper and lower braces 11—12 are secured by rivets 13 and 14.

Fig. 4 shows a modified form wherein the outer edge of the member 10 is provided with a flange 16 which increases the strength of the joint between the upper and lower flanges 5—6 and also stiffens this edge against buckling. This plate member may extend around the corner (17) of the car so that the thrust against the end wall is partially transmitted directly through the member to the diagonal braces independently of the rivets. The horizontal cross section of the member is then of Z-formation which is very strong mechanically.

Fig. 5 shows a modified form wherein the member 20, upper and lower diagonal braces 21—22 are made of a single angle bar bent to the desired form.

Fig. 6 shows a modified form wherein the member 30 is provided with an aperture 31 through which a diagonal brace rod 32 protrudes and is secured by a nut 33 to provide a loose connection therebetween. The opposite ends 34 of these respective rods are similarly secured to the side plate and side sill, 100

respectively, by a brace anchor 34 having a flange 35 provided with an aperture through which the rod extends and is secured thereto to provide a loose connection therebetween. The companion flange 36 braces the flange.

Fig. 7 shows a modification of Fig. 6 where in the member 40 is made of a casting and has a flange 41 overlapping a part of the front wall of the car and is provided with reinforcing ribs 42.

Fig. 8 shows a modified form for use on a double sheathed box car wherein the diagonal brace rods 50 are positioned between the lining and sheathing of the side wall of the car and the flange 51 of the member 52 and also the end wall of the car are provided with apertures through which the rods extend and are secured thereto by nuts.

When the braces extend through the members (30—40—52) and/or anchor 34 a certain amount of looseness is obtained which permits the car to weave and flex without bending or distorting the braces or associated parts. Such constructions are shown in Figs. 6 to 8 inclusive. The brace may be rigidly secured at one end and loosely attached at its opposite end and still obtain these desired results.

I have described my invention in connection with a box car but it is also applicable to gondola cars wherein the side truss comprises upper and lower chords.

The accompanying drawings illustrate the preferred form of the invention, though it is to be understood that the invention is not limited to the exact details of construction shown and described, as it is obvious that various modifications thereof within the scope of the claims will occur to persons skilled in the art.

40. I claim:

1. In a railway car having upper and lower frame members, the combination of an end wall comprising two metallic plates secured together along a horizontal line, each of said plates provided with a flange adjacent a vertical margin, a member connected to the flange of each plate, and upper and lower diagonal braces, each having one end attached to said member, one of said braces having its opposite end attached to said upper frame member and the other of said braces having its opposite end secured to said lower frame member.

2. In a railway car having upper and lower frame members, the combination of an end wall comprising two metallic plates secured together along a horizontal line, each of said plates provided with a flange adjacent a vertical margin, a member connected to the flange of each plate, and upper and lower diagonal braces, each having one end loosely attached to said member, one of said braces having its opposite end attached to said upper frame member and the other of said braces having

its opposite end secured to said lower frame member.

3. In a railway car having upper and lower frame members, the combination of an end wall comprising two metallic plates secured together along a horizontal line, each of said plates provided with a flange adjacent a vertical margin, a member connected to the flange of each plate, and upper and lower diagonal braces, each having one end loosely attached to said member, one of said braces having its opposite end loosely attached to said upper frame member and the other of said braces having its opposite end loosely secured to said lower frame member.

4. In a railway car having upper and lower frame members, the combination of an end wall comprising two metallic plates secured together along a horizontal line, each of said plates provided with a flange adjacent a vertical margin, a member connected to the flange of each plate having an outwardly extending flange at one edge, and upper and lower diagonal braces, each having one end attached to said member, one of said braces having its opposite end attached to said upper frame member and the other of said braces having its opposite end secured to said lower frame member.

5. In a railway car having upper and lower frame members, the combination of an end wall comprising two metallic plates secured together along a horizontal line, each of said plates provided with a flange adjacent a vertical margin, a member connected to the flange of each plate having an outwardly extending flange at one edge and an inwardly extending flange at the other edge which overlaps the end wall, and upper and lower diagonal braces, each having one end attached to said member, one of said braces having its opposite end attached to said upper frame member and the other of said braces having its opposite end secured to said lower frame member.

6. In a railway car having upper and lower frame members, the combination of an end wall comprising two metallic plates secured together along a horizontal line, each of said plates provided with a flange adjacent a vertical margin, a member connected to the flange of each plate provided with apertures, and upper and lower diagonal braces passing through the apertures in said member, one of said braces having its opposite end attached to said upper frame member and the other of said braces having its opposite end secured to said lower frame member.

7. In a railway car having upper and lower frame members, the combination of an end wall comprising two metallic plates secured together along a horizontal line, each of said plates provided with a flange adjacent a vertical margin, a member connected to the flange of each plate provided with apertures,

upper and lower anchors secured to said upper and lower frame members, respectively, provided with apertures, and upper and lower diagonal braces passing through the apertures in said member, one of said braces having its opposite end passing through the aperture in said upper anchor and the other of said braces having its opposite end passing through the aperture of said lower anchor.

8. In a railway car having upper and lower frame members, the combination of an end wall comprising two metallic plates secured together along a horizontal line, each of said plates provided with a flange adjacent a vertical margin, a member connected to the flange of each plate, upper and lower anchors secured to said upper and lower frame members, respectively, provided with apertures, and upper and lower diagonal braces, each having one end attached to said member, one of said braces having its opposite end passing through the aperture in each upper anchor and the other of said braces having its opposite end passing through the aperture of said lower anchor.

9. In a railway car having upper and lower frame members, the combination of an end wall comprising two metallic plates secured together along a horizontal line, each of said plates provided with a flange adjacent a vertical margin and formed with integral horizontal embossments, a member connected to the flange of each plate, and upper and lower diagonal braces, each having one end attached to said member, one of said braces having its opposite end attached to said upper frame member, and the other of said braces having its opposite end secured to said lower frame member.

10. A metallic plate wall for a railway car having a flange at one vertical edge secured to the upper and lower longitudinal frame members, respectively, of the car forming the corner post of the car, a reinforcing member attached to the flange between said frame members, and a pair of upwardly and downwardly extending braces, each having one end secured to said member, one of said braces having its opposite end secured to said upper frame member and the other of said braces having its opposite end secured to said lower frame member.

11. A metallic plate wall for a railway car having a flange at one vertical edge secured to the upper and lower longitudinal frame members, respectively, of the car forming the corner post of the car, a reinforcing member attached to the flange between said frame members, and a pair of upwardly and downwardly extending braces, each having one end loosely secured to said member, one of said braces having its opposite end secured to said upper frame member and the other

of said braces having its opposite end secured to said lower frame member.

12. A metallic plate wall for a railway car having a flange at one vertical edge secured to the upper and lower longitudinal frame members, respectively, of the car forming the corner post of the car, a reinforcing member attached to the flange between said frame members, and a pair of upwardly and downwardly extending braces, each having one end loosely secured to said member, one of said braces having its opposite end loosely secured to said upper frame member and the other of said braces having its opposite end loosely secured to said lower frame member.
